UNITED STATES PATENT OFFICE.

ALBERT F. MADDEN, OF NEWARK, NEW JERSEY.

REPEATING PHONOGRAPH.

1,144,219.

Specification of Letters Patent. Patented June 22, 1915.

Application filed December 9, 1914. Serial No. 876,239.

To all whom it may concern:

Be it known that I, ALBERT F. MADDEN, a citizen of the United States, residing in the city of Newark, county of Essex, and 5 State of New Jersey, have invented certain new and useful Improvements in Repeating Phonographs, of which the following is a full and clear specification.

My invention relates in general to the repeating mechanism of phonographs and more especially to mechanical repeating mechanism which is automatic in its operation.

15 Phonographs are employed for rendering dance music and for such purposes it is desirable to repeat the music indefinitely. While, of course, my invention is applicable to repeating phonographs for whatever purpose they may be employed, I refer to 20 their use for rendering dance music as this field is one in which the automatic repeating of the selection is perhaps most desired.

The object of the invention is to provide 25 a simple and inconspicuous attachment for phonographs by which the reproducer, when the needle arrives at the end of the record, is automatically returned to the starting 30 position and then released so that the continued operation of the phonograph proper will result in the selection being repeated.

According to my invention, the mechanism can be adjusted to cause the actuation 35 of the repeat mechanism with great accuracy to suit the exact length of each selection to be reproduced. The construction also provides for the removal of the reproducer needle from the record groove prior 40 to the return of the reproducer to starting position, and the gradual introduction of the needle into the record groove at the completion of the return movement, so that injury to the record is avoided.

A prominent feature of the invention is 45 the use of the surface of the record itself for operating the return member. This is effected by the provision of a yielding re- 50 silent roller which is automatically thrown into engagement with the surface of the record at the end of the selection, and is held with its axis of rotation inclined to the record groove so that by the rotation of

the record, the roller is caused to veer rapidly out of the path of the successive grooves until the reproducer arrives at starting position where the return member is withdrawn from contact with the record, and the reproducing needle is again gradually introduced into the groove. 55

The invention is applicable to sound reproducing machines of either disk or cylinder type herein referred to as phonographs, but to clearly illustrate the principles thereof I shall describe the same with reference to an embodiment thereof in a disk machine, provided with the usual articulated repro- 60 ducer arm.

In the drawings, Figure 1 is a plan view of the repeating mechanism; Fig. 2 is a side elevation thereof with parts in section, the device being shown in normal position; Fig. 70 3 is a similar view with the parts shown in the automatic return position. Fig. 4 is a detail front elevation of the automatic return roller; Fig. 5 is a similar view of the dash pot with its setting member and Fig. 6 75 is a detail elevation showing the tripping mechanism for controlling the inauguration of the return movement.

Referring more specifically to said drawing, 10 indicates the ordinary box or housing of the phonograph, 11 the turn table and 12 a disk record. The usual sound chest or bracket 13 supports the reproducer arm 14 which has as its outer end the U-tube 15, carrying the box 16 and needle 17. These 80 parts are herein referred to as the reproducer. The automatic return roller 18 is journaled in a forked knee lever 19, which is fulcrumed at 20 upon a bracket 21 made fast to U-tube 15 by means of the split ring 85 clamp 22. The position of bracket 21 on U-tube 15 is readily adjusted by means of the wing bolt 23, which controls the clamp. Knee lever 19 has an arm 24 engaged by a leaf spring 25, suitably mounted on the split 90 ring clamp 22, by which the roller 18 is normally held out of engagement with the record. It will be observed from reference to Fig. 1 that the roller 18 is so inclined to the record groove that clockwise movement 95 of the record 12 will cause the same to veer toward the outer edge of the disk. During 100

such travel, the roller 18 rotates upon its axis so that very little power is required to return the reproducer to starting position.

With the mechanism thus far described, it will be seen that the roller 18 is normally held clear of record 12 in idle position by means of its return spring 25, and that with this mechanism the automatic repeating or resetting operation can be automatically controlled by suitably controlling the position of the roller 18. For accomplishing this result, I therefore provide automatic mechanism for throwing roller 18 into operative engagement with the record 12 when the needle arrives at the end of the record, and for gradually releasing the roller 18 to the return action of its leaf spring 25 when the reproducer has arrived in starting position. Under the broad scope of my invention, the roller 18 may be thrown into operation by any suitable means, but I have herein shown a control mechanism which operates successively and of which some of the features are referred to as special features of the invention.

Mounted upon the sound chest or trunk 13 is a stationary plate or table 26, provided with slots 27 and 28 for the reception of an adjustably fixed stop 29 and an adjustably fixed trip member 30. These stop and trip members are secured in place by means of the thumb screws 31 and 32, and it will be understood that they are adjusted to assume positions corresponding with the commencement and ending of the record, as will be hereinafter explained. Above the stationary plate 26, a frame 33 is firmly clamped upon the swinging reproducer arm 14 by means of a split ring collar portion 34 and clamp screw 35. A lever 36 is fulcrumed upon frame 33 by means of a screw post 37. Lever 36 has one of its ends bent downward into the plane of stop 29 and bifurcated to form a cam finger 38 and stop finger 38'. The other end of lever 36 is normally held behind trigger 39 pivoted to frame 33 on screw 40 and held in lever retaining position by leaf spring 41 also secured to frame 33 (see Figs. 1 and 6). Trigger finger 39 extends downwardly into the path of the adjustable trip plate 30 above referred to, whereby lever 36 is released from trigger 39 as will be seen. Lever 36 serves as the tensioning and control member for a spring which throws the return roller 18 into operation. This spring is represented at 42 and is fixed at one end to a split ring collar 43 clamped upon the outer end of sound arm 14 in which the U-tube 15 turns. The other end of spring 42 is held behind the lock nut 44 of a threaded socket 45. Socket 45 is pivoted to lever 36 at the screw 46, so that it will be seen that the spring 42 when under tension, holds the end

of the lever 36 against the trigger 39, and that when trigger 39 is tripped, the spring 42 swings the bifurcated end 38, 38' of lever 36 inward. This occurs when the reproducer has reached the end of the record and the bifurcated end of lever 36 is some distance from stop 29. Upon the approach of the reproducer, to starting position, the outer end of cam finger 38 will thereupon engage with the stop 29 which is provided with an anti-friction roller as illustrated, and restore the tension to spring 42. The resetting of the other end of lever 36 behind the trigger 39, ready for another operation, is thus accomplished without shock to the reproducer. Stop finger 38' serves positively to arrest the reproducer upon its arrival at starting position. The mechanism herein shown, by which the tension of spring 42 is applied to throw in the return roller 18 comprises a push rod 47, which is adjustably threaded into socket 45 and slidably positioned in a block 48 (see Figs. 1 and 5) integral with or secured to the cylinder 49 of a dash pot. Block 48 and dash pot cylinder 49 are secured to a flange 50 of the split ring clamp 43 by means of a bolt and nut 51. Push rod 47 has a ball 52 secured on its outer end. This ball 52 engages a plate 53 which is secured on the end of the piston 54 of the dash pot, which piston is herein illustrated as provided with a leather cup washer 55 and operating to expel air from cylinder 49 (Fig. 2), through a discharge port 56 regulated by the needle valve 57. When spring 42 is released by the tripping of trigger 39, the push rod 47 sets the dash pot and at the same time engages a flange 58 formed on knee lever 19, and thus throws the return roller 18 into operative engagement with the face of record 12. This operation coincidentally raises the needle 17 out of the record groove and the return of the reproducer to starting position is thus inaugurated.

During the return of the reproducer, the bifurcated end of lever 36 is held inward so when the reproducer nears starting position the cam finger 38 engages the anti-friction roller of stop 29 and the lever 36 is thereby gradually restored to normal position with the spring 42 under tension and the lever locked by trigger 39. After the resetting of spring 42 and lever 36, the dash pot 49, 54 is released from the push rod 47, and the dash pot assumes control of return roller 18. The pressure of return spring 25 on arm 24, together with the weight of the end of the reproducer, gradually induces the discharge of air from the dash pot until the needle 17 has been returned to the record groove and simultaneously the roller 18 is raised from the record 12 into normal position.

With the apparatus described, I provide

for the automatic resetting and repeating of the selection indefinitely without other attention than the initial adjustment of the stops, and winding of the spring motor 5 when such is employed. It will be apparent that the operation of the resetting mechanism is not dependent upon any particular form of phonograph drive and none is herein specifically shown.

10 I believe that the employment of the record itself without alteration or addition, for effecting the return movement of the reproducer, is broadly new in my present invention and therefore I do not wish to be 15 understood as limiting the invention to any specific construction of the return roller or member, or the mechanism by which this is thrown into and out of operative engagement with the record. Another feature of novelty 20 resides in the use of the return of the reproducer by the motion of the record, to store in the spring 42 the power necessary to throw the return means into tractive engagement with the record.

25 I claim:

1. A repeating phonograph comprising in combination a reproducer, an operating support for a record, a roller operated by the record for returning the reproducer to starting position, and automatic means for throwing said return roller into and out of operative engagement with the record.

2. A repeating phonograph comprising in combination a reproducer, an operating support for the record, a return roller mounted on said reproducer and movable into operative engagement with the record at inclined relation to the record groove, for raising the needle and returning the reproducer to starting position and automatic means for moving said return roller into and out of such operative engagement.

3. A repeat mechanism for phonograph reproducers, comprising in combination a yielding roller for returning the reproducer to starting position, a knee lever in which said roller is mounted, for elevating and supporting the needle during the return of the reproducer, means for setting said roller in contact with and inclined to the record groove for actuation thereby, means for withdrawing said setting means from said roller, and means for removing said roller from the record groove.

55 4. A repeat mechanism for phonograph reproducers, comprising in combination a yielding roller for returning the reproducer to starting position, a knee lever in which said roller is mounted, for elevating and supporting the needle during the return of the reproducer, means for attaching said knee lever to the reproducer, means mounted on the reproducer for normally holding said roller out of contact with the record

groove, means for setting said roller in contact with and inclined to the record groove for actuation thereby and means for withdrawing said setting means from said roller.

5. A repeat mechanism for phonograph reproducers, comprising in combination a yielding roller for returning the reproducer to starting position, a knee lever in which said roller is mounted, for elevating and supporting the needle during the return of the reproducer, means for setting said roller in contact with and inclined to the record groove for actuation thereby, means for withdrawing said setting means from said roller, means for removing said roller from the record groove, and means for cushioning the return of the needle to the record groove.

6. A repeat mechanism for phonograph reproducers, comprising in combination a yielding roller for returning the reproducer to starting position, a knee lever in which said roller is mounted, for elevating and supporting the needle during the return of the reproducer, means for attaching said knee lever to the reproducer, means mounted on the reproducer for normally holding said roller out of contact with the record groove, means for setting said roller in contact with and inclined to the record groove for actuation thereby, means for withdrawing said setting means from said roller and a dash pot for retarding the return of said roller to normal position.

7. A repeating phonograph comprising in combination a reproducer, an operating support for a record, an automatic return roller actuated by the record groove, means for setting said return roller in operative engagement with the record groove, and adjustable means for controlling the operation of said setting means.

8. A repeating phonograph comprising in combination a record actuating support, a reproducer adapted to follow the record, automatic return means mounted on said reproducer and movable into contact with the record groove for returning the reproducer to starting position, means for restoring said return means to normal position out of contact with the record, means for setting said return means in contact with the record groove for actuation thereby, means for withdrawing said setting means from said return means and causing the return of the reproducer to store power in said setting means for a subsequent operation and means for retarding the restoration of said return means to normal position.

9. A repeating phonograph comprising in combination a record actuating support, a reproducer, means actuated by engagement with the record groove to return the reproducer to starting position, a spring moving with the reproducer and having suitable con-

nections for moving said return means into engagement with the record groove, a lever moving with the reproducer and pivotally connected with said spring, a cam finger 5 projecting from said lever, a stationary stop engaged by said cam finger during the return of the reproducer, for storing power in said spring, means for locking said lever

with the spring under tension, and a stationary stop for withdrawing said locking 10 means from said lever.

ALBERT F. MADDEN.
